SUPPORTING BASES FOR CYLINDER BED MACHINES

Martin R. Perla, Bridgeport, Conn., assignor to The Singer Manufacturing Company, Elizabeth, N.J., a corporation of New Jersey

Filed Feb. 13, 1956, Ser. No. 565,122

7 Claims. (Cl. 112—260)

This invention relates to sewing machines, and more particularly, to a novel base construction for supporting and stabilizing a portable sewing machine during use.

Those sewing machines which are intended to be portable in the sense that they are intended to be fully operative on any supporting surface such as a table top, desk, counter-top or the like, present serious problems of support and stability, which problems are not encountered with sewing machines mounted in supporting cabinets especially designed to receive the machine. These support and stability problems of portable sewing machines are particularly acute as they pertain to the so-called cylinder bed sewing machine, that is, a sewing machine having a projecting work supporting arm provided with a free end adapted to accommodate tubular articles to be stitched.

In the usual cylinder bed machine, the base of the machine frame which constitutes a continuation of the machine standard, is insufficient in and of itself to support the machine with proper stability since it is small in base area and offset to one side of the stitching point. The various supporting structures known in the prior art for supplementing the base of the machine frame in supporting cylinder or free arm sewing machines are disadvantageous in that they either minimize the space available for the flow of work fabrics around the free arm, or they make it necessary that the free arm be positioned in a superelevated position in order to provide the requisite clearance space, which abnormally high position not only makes the machine more difficult and awkward to use but also raises the center of gravity of the machine with consequent tendency toward greater instability.

It is an object of this invention to provide a novel supporting base for a portable sewing machine, which supporting base is particularly well adapted for use with a free arm type sewing machine.

It is also an object of this invention to provide a supporting base for a free arm type sewing machine which does not detract from the space available for the flow of work between the free arm and the surface upon which the machine is supported so that the free arm need not be superelevated to compensate for any loss of work space beneath the arm occasioned by the presence of the supporting base.

With the above and other objects and advantages in view as will hereinafter appear, this invention comprises the devices, combinations, and arrangements of parts hereinafter described and illustrated in the accompanying drawings of preferred embodiments thereof in which:

Fig. 1 is a front elevational view of a sewing machine having applied thereto a supporting base embodying my invention.

Fig. 2 represents a cross sectional view taken substantially along line 2—2 of Fig. 1 and illustrating the top plan view of the work supporting arm and the supporting base of the sewing machine.

Fig. 3 is a cross sectional view taken substantially

2

along a left end elevational view of the line 3—3 of Fig. 2 with a portion of the supporting base being broken away to illustrate the fastening means.

Fig. 4 is a front elevational view of a portion of a sewing machine having a modified form of supporting base applied thereto.

Fig. 5 represents a bottom plan view of that portion of the sewing machine illustrated in Fig. 4.

Fig. 6 is a cross sectional view taken substantially along line 6—6 of Fig. 5 and

Fig. 7 is an enlarged cross sectional view taken substantially along the line 7—7 of Fig. 5.

Referring to the drawings, this invention in preferred form is applied to a sewing machine having a free work supporting arm 11 or a cylinder bed as it is also commonly referred to in the art. The work supporting arm extends laterally outwardly from a machine base 12 of which a vertical continuation forms a standard 13 carrying a bracket arm 14 which overhangs the work supporting arm. As a matter of convenience of manufacture, the base and the standard may be fabricated separately, but in any event the standard and base when assembled are locked together to form an integral standard unit from which the work supporting arm extends.

This invention is not concerned with the particular form of stitch forming mechanism of the sewing machine, and therefore, any conventional type of stitch forming instrumentalities may be used. The sewing machine illustrated in the drawings is fitted with stitch forming mechanisms of a type well known to those skilled in the art in which a needle 15 is carried by a needle bar 16 journaled for endwise reciprocatory movement in the bracket arm 14. The needle cooperates in the formation of stitches with stitch forming mechanism (not shown) carried in the work supporting arm, the work fabrics being pressed against a work feeding dog 17 in the work supporting arm by a presser foot 18 carried by a presser bar 19 supported in the bracket arm.

This invention relates to a novel supporting base construction effective to provide a stable support for the sewing machine when placed directly upon any flat surface, such as a table top, desk, counter, etc. Figs. 1, 2 and 3 of the drawings illustrate one preferred form of the supporting base constructed in accordance with this invention and Figs. 4, 5, 6 and 7 illustrate a slightly modified form of construction.

Referring to Figs. 1, 2 and 3, the supporting base comprises a continuous member 25 of substantially uniform cross sectional configuration and formed into a closed loop. A pair of cross braces 26—26 are welded or otherwise secured across the loop provided by the support member 25, which braces accommodate fastening bolts 27—27 by which the support member is fastened to the base of the machine frame beneath the standard.

In the drawings a tubular support member of circular cross sectional shape is shown. The tubular form is advantageous for its lightness, particularly as applied to a portable sewing machine, and the circular cross sectional shape is preferable since it provides for an easy flow of work fabrics over the supporting base and minimizes interference and catching of buttons and other objects which may be associated with the fabrics being stitched. It will be appreciated, however, that this invention is not necessarily limited to this preferred form and cross-sectional configuration inasmuch as a solid support member of non-circular cross section might also be used effectively.

The supporting member 25 is formed in a flat loop; that is, its under surfaces are co-planar, so that continuous engagement will be made with any flat surface upon which the sewing machine may be placed. A plurality of pads 29—29 of flexible cushioning material such as

rubber, felt, or the like may, however, be affixed beneath the support member to prevent marring or scratching of the table top or other surfaces upon which the sewing machine may be placed. As illustrated in Fig. 3, the cushion pads 29-29 are formed each with a shank 30 adapted to be forced into an aperture provided on the under surface of the support member 25. Expansion of the shank 30 within the tubular support member 25 will lock the cushion pad 29 in place.

Since the support member has the form of a flat loop, the under surface of the cushioning pads 29-29 are co-planar and define a plane of support Y-Y for the sewing machine. Should the pads 29-29 be disposed with, the plane of support would coincide with the under surface of the support member 25 and, in any event, the support member 25 since it carries the pads 29-29 can be said to define the plane of support Y-Y. Fig. 2 is a plan view of the work supporting arm 11 of the sewing machine together with the supporting member 25 taken normal to the plane of support Y-Y. The work supporting arm 11 of the sewing machine corresponds in Fig. 2 to its projection normal to the plane of support Y-Y, and as illustrated in Fig. 2, the support member 25 is disposed completely outside the projection of the work supporting arm normal to the plane of support. The loop formed by the support member thus defines an aperture which contains the projection of the work supporting arm normal to the plane of support. In terms of the results of this form of construction, a machine supporting base is provided which leaves clear the space beneath the work supporting arm; that is, the clearance space of passage of work fabrics beneath the work supporting arm 11 of the sewing machine is unaffected by the presence of the support member 25 and would be no greater were the support member 25 to be removed entirely.

Referring to Figs. 1 and 3, the support member 25 is preferably disposed beneath the level of the work supporting arm of the sewing machine so that the work fabrics in passing around the free arm need not follow a tortuous path in which they are apt to catch, snag or be otherwise impeded, but in which they may flow freely about the arm. The support member 25, as illustrated in these figures, extends vertically from the plane of support Y-Y only a portion of the distance between the plane of support and the work supporting arm of the sewing machine.

Figs. 4, 5, 6 and 7 illustrate a slightly modified form of construction embodying this invention. In the modified form, a support member 35 in the form of a continuous U-shaped loop is used. The support member is preferably of tubular material with uniform cross sectional shape, one free extremity of the U-shaped support member being secured beneath the front of the machine frame base or standard and the other free extremity being secured beneath the rear thereof by fastening bolts 36-36. As illustrated in Fig. 7, the tubular support member 35 is apertured to receive the fastening bolts 36 and a washer 37 is provided on each fastening bolt 36. The washers 37 are preferably formed with the contour of the bore of the tubular support member.

Cushioning pads 39-39 may be secured to the support member 35, as in the construction illustrated in Figs. 1, 2 and 3. The cushioning pads beneath the machine base 12 may, if desired, be fitted directly to the machine base itself, as illustrated in Figs. 4 and 5.

As in the embodiment illustrated in Figs. 1, 2 and 3, the form illustrated in Figs. 4, 5, 6 and 7 provides a machine supporting base extending outside the projection of the work supporting arm 11 normal to a plane of support Y-Y defined by the supporting base 35, and the supporting base 35 occupies only a portion of the vertical distance between the plane of support Y-Y and the work supporting arm 11.

The supporting base in accordance with this invention

thus provides both stability of support for the sewing machine as well as a maximum of clearance, facilitating passage of fabrics around the work supporting arm of a cylinder bed sewing machine.

Having thus set forth the nature of the invention, what I claim herein is:

1. In combination with a sewing machine having a standard, a free ended work-supporting cylinder bed extending from said standard and adapted to accommodate tubular articles, said cylinder bed having an upper work-supporting surface and an under surface, and stitch forming instrumentalities carried by said standard and said cylinder bed defining a stitching point on said cylinder bed, a supporting base comprising a loop-shaped member secured to said standard and defining a plane of support for said sewing machine beneath the under surface of said cylinder bed, said member extending from said standard and disposed wholly outside the projected area of said work-supporting cylinder bed normal to said plane of support, and said member outwardly of the stitching point toward the free end of said cylinder bed extending from the plane of support only a portion of the distance between said plane of support and the under surface of said cylinder bed.

2. In combination with a sewing machine having a standard, a free ended work-supporting cylinder bed extending from said standard and adapted to accommodate tubular articles, and stitch forming instrumentalities carried by said standard and said cylinder bed defining a stitching point on said cylinder bed, a supporting base comprising a member secured to said standard and defining a plane of support for said sewing machine, beneath said cylinder bed, said member being formed to define an aperture encompassing the projected area of said work-supporting cylinder bed normal to said plane of support.

3. In combination with a sewing machine having a standard, a free ended work-supporting cylinder bed extending from said standard and adapted to accommodate tubular articles, said cylinder bed having an upper work-supporting surface and an under surface, and stitch forming instrumentalities carried by said standard and said cylinder bed defining a stitching point on said cylinder bed, a supporting base comprising a member secured to said standard and defining a plane of support for said sewing machine, said member being formed with a loop-shaped portion of substantially uniform cross-sectional shape extending from said standard to define an aperture encompassing the projected area of said work-supporting cylinder bed normal to said plane of support, and said member extending upwardly from the plane of support only a portion of the distance between said plane of support and the under surface of said cylinder bed.

4. The combination set forth in claim 2 in which the supporting base comprises a member having the form of a U-shaped loop with spaced free extremities, and means for securing each free extremity of said loop beneath said standard to define said aperture encompassing said projected area of the work-supporting cylinder bed.

5. The combination set forth in claim 3 in which the supporting base comprises a member having the form of a U-shaped loop with spaced free extremities shaped to encompass on three sides a space as large as that occupied by the projected area of said work-supporting cylinder bed normal to said plane of support, and means for securing each free extremity of said loop beneath said standard to define said aperture encompassing said projected area of the work-supporting cylinder bed.

6. The combination set forth in claim 2 in which the supporting base comprises a member having the form of a closed loop shaped to enclose a space larger than the projected area of said work-supporting cylinder bed normal to said plane of support, and means for securing said closed loop shaped member beneath said standard with

said enclosed space encompassing said projected area of the work-supporting cylinder bed.

7. The combination set forth in claim 3 in which the supporting base comprises a member having the form of a closed continuous loop shaped to encompass on all sides a space larger than that occupied by said projected area of said work-supporting cylinder bed on said plane of support, and means for securing said closed loop shaped member beneath said standard with said enclosed space

encompassing said projected area of the work-supporting cylinder bed.
